(57) **CLAIM**

We claim the ornamental design for a handheld control, as shown and described.

DESCRIPTION

FIG. 1 is a top perspective view of the handheld control of the present invention;

FIG. 2 is a bottom perspective view of the handheld control of the present invention;

FIG. 3 is a front elevation view of the handheld control of the present invention;

FIG. 4 is a rear elevation view of the handheld control of the present invention;

FIG. 5 is a left side elevation view of the handheld control of the present invention;

FIG. 6 is a right side elevation view of the handheld control of the present invention;

FIG. 7 is a top plan view of the handheld control of the present invention; and,

FIG. 8 is a bottom plan view of the handheld control of the present invention.

The ornamental design which is claimed is shown in solid lines in the drawings. Any broken lines in the drawings are for illustrative purposes only and form no part of the claimed design.
